UNITED STATES PATENT OFFICE.

EVELYN F. FRENCH AND MILTON C. JEFFERS, OF NEW YORK, N. Y.

SOUND-DEADENING ATTACHMENT FOR RAILWAY-CARS.

SPECIFICATION forming part of Letters Patent No. 284,265, dated November 9, 1880.
Application filed September 25, 1879.

To all whom it may concern:

Be it known that we, EVELYN F. FRENCH and MILTON CLIFFORD JEFFERS, both of the city, county, and State of New York, have invented certain new and useful improvements in means, and the mode of applying the same, for deadening or reducing sound in railway-structures caused by moving carriages thereon; and we do hereby declare that the following specification, taken in connection with the drawings furnished and forming a part thereof, is a full, clear, and exact description thereof, sufficient to enable others skilled in the art to practice the same.

Our invention consists in the method of deadening sound, diminishing friction, and preventing wear on railways, consisting in applying lead to the surface of the rails at the points of contact with the wheels or in advance of the same.

The invention further consists in certain devices employed for that purpose, and herein-after more particularly set forth and claimed.

To enable others to more fully understand and practice our said invention, we will describe the same in detail.

Referring to the drawings, Figure 1 represents a portion of the frame of a car with section cut away above the wheel, showing a pocket, within which a ball of lead is located, resting and operating upon said wheel by its own gravity, and a vertically-arranged projection, within which is a traversing wheel or small roller. Fig. 2 is the same as Fig. 1 without the small wheel or roller.

A represents a portion of the frame of the truck of a railway-car; B, the flange which supports the box or the journal of the axle and wheel.

C represents the wheel, of the usual form; D, a ball of lead resting upon and revolved by the motion of the wheel.

E represents a pocket or opening, within which the ball is held secured.

F represents a vertically-arranged bracket, 45 supporting a small leaden roller or wheel, G, resting upon the track and rotated by the forward movement of the car.

H represents the rail, and H' fish-bar or a wooden tie.

The leaden wheel G and the leaden ball D operate to check the vibrations and deaden the sound of the wheels on the rails. This is their chief function. Their attrition on the rail and wheel, of course, transmits some small 55 portion of their material to the surfaces in contact, and thereby tends to lessen friction and prevent wear. As these devices may be applied to all the running wheels of a train, their collective effect upon the rail-surface will be considerable, and the application of the lead will, of course, be repeated with the passage of every 60 train of cars on a road where these improvements have been adopted.

The wheel G and ball D take the place of 65 long strips of material extending under or within the rails, such as have heretofore been used; but for further deadening effect we may obviously employ such strips also, and it is often convenient to arrange them against the 70 sides of the rails.

What we claim is—

1. A leaden wheel carried by a car and rotating against the top of the rail, substantially as set forth.

2. A leaden ball carried by a car and resting on the top of a car-wheel, substantially as set forth.

EVELYN F. FRENCH.
MILTON CLIFFORD JEFFERS.
